UNITED STATES PATENT OFFICE.

CLARENCE L. THOMPSON, OF PORT WASHINGTON, NEW YORK.

CAR-SEAT.

1,196,902.

Specification of Letters Patent.

Patented Sept. 5, 1916.

Application filed March 31, 1915. Serial No. 18,224.

To all whom it may concern:

Be it known that I, CLARENCE L. THOMPSON, a citizen of the United States, and resident of Port Washington, county of Queens, 5 and State of New York, have invented certain new and useful Improvements in Car- Seats, of which the following is a specification.

The object of this invention is to provide 10 a car seat of the swinging back type, and to simplify and improve the construction thereof.

Another object of the invention is to provide means for supporting the back of the 15 seat in its forward and rearward positions, whereby the strains brought upon the back will be directly transmitted to the supporting frame.

Another object of the invention is to provide 20 a car seat having a rocking back of the parallel lever type of reversing mechanism, with means for relieving the said levers of the strains brought on the back.

Another object of the invention is to provide 25 a simplified and improved means for supporting the cushion on rocker arms adapted to be simultaneously operated to bring the cushion to the proper position as the back is swung from one position to another.

Another object of the invention is to provide 30 simplified means for swinging the foot rest simultaneously with the operation of swinging the back.

Another object of the invention is to provide 35 a car seat construction wherein the various parts will be connected together so that they may be readily dismantled, thus facilitating the repairing and reassembling of the parts of the seat.

In the drawings, Figure 1 is a transverse vertical sectional view of the car seat, the back support being broken away and the cushion of the seat being shown in dotted lines only; Fig. 2 a similar view showing the back in its midway position to permit of the removal of the cushion; Fig. 3 a central vertical sectional view on the line III—III of Fig. 2; Fig. 4 a vertical sectional view on the line IV—IV of Fig. 1; Fig. 5 a detail view showing the method of attaching the connecting rails to the end plates of the frame of the seat; Figs. 6 and 7 detail views of the crank arm which moves the cushion rocker arms when the back is moved from one position to another; Fig. 8 a detail perspective

view of the cushion rocker arms and the means for locking said arms to the cushion; Fig. 9 a detail view showing the means for attaching the connecting rails to the top of 60 the pedestal; Fig. 10 a detail view partly in section of a portion of one of the back supporting bars and the connected back standard; Fig. 11 a side elevation partly in section of the parts shown in Fig. 10; Fig. 12 65 a detail view of the lower end of the back supporting bar; Fig. 13 a side elevation of the parts shown in Fig. 12; and Fig. 14 a detail view of the outer side of the lower 70 end of the back standard.

Referring to the various parts by numerals, 1 designates the pedestal which supports the car seat at the aisle end thereof, the other end of the seat being supported on the side of the car body in the usual manner. The 75 connecting rails 2 are mounted in the upper ends of the arms of the pedestal, the ends of said rails fitting in sockets 3 carried by the end plates 4 of the seat structure. These connecting rails are preferably cylindrical and 80 tubular and are provided at their ends with pins 5 which are adapted to fit and slide in bayonet slots 6 formed in the sockets 3, the sockets being secured to the plates 4. By this means the connecting rails are detachably secured in the sockets and may be readily removed therefrom. The pedestal arms are provided with locking screws 8 which 85 contact with the connecting rails at a point above their horizontal centers, whereby said connecting rails are locked in the sockets in the tops of the pedestal arms, as shown clearly in Fig. 9. By releasing the locking screws 8 said rails may be turned and then 90 detached from the sockets 3.

Rotatably mounted in the end plates 4 is 95 the operating rod 9 the ends of said rod fitting in sockets 10 secured to the inner sides of the plates 4. Mounted on the operating rod near the ends thereof are back-supporting bars 11, said bars having the circular enlargement 12 at their upper ends, said enlargement being formed with the outwardly extending circular flange 13, said flange extending around the said circular enlargement and terminating at the side edges of the bar 11. Pivoted to each end frame on opposite sides of the bearing 10 for the operating rod are the lower ends of two parallel levers 14. These levers are pivoted at points 100 equally distant from the center of the operating rod and the centers of said pivots are 105

in a plane passing horizontally through the center of the operating rod. The upper ends of these parallel levers are mounted on studs 15 secured to the lower end of the 5 back standard 16. This standard is pivotally secured to the back-supporting bar 11, on pivot 19 in the center of the enlargement 12 of said bar. The back standard 16 is formed with a circular flange 17 which fits within 10 the flange 13 of bar 11, the flange 17 extending partially around the enlarged circular end 18 of the standard 16, whereby as the back is rocked in its swinging movement from one position to the other the flange 17 15 will always be in contact with the flange 13 and will not extend across the space between the lower ends of the said flange 13. The studs 15 are located equal distances from the center of the pivot 19 and are a slightly 20 greater distance apart than the pivots at the lower ends of the arms 14. The levers 14 are bent outwardly at their ends, the main bodies of them lying close together and slightly overlapping during the movements 25 of the back. These parallel levers maintain the back standard 16 in proper position during its swinging movement from one side of the seat to the other. The pivots 15 being a slightly greater distance from the pivot of 30 the back support than the pivots at the lower ends of the levers 14 are from the pivot of the bar 11, the back standard will be given a slight inclination when it is thrown to either of its positions, as shown clearly in Fig. 1. 35 The back-standard 16 near its lower end, and across the circular enlargement 18, is formed with an outwardly extending flange 20 which is adapted to come to rest on the slightly inclined flange 21 of the adjacent end plate, as 40 shown clearly in Figs. 1, 3 and 4 of the drawings. The inclination given to the back standard by reason of the arrangement of the pivots 15 is sufficient to permit the flange 20 to seat squarely on the flange 21 and thereby 45 permit the back standard 16 to incline upwardly and rearwardly the desired amount. It will be noted that when the flange 20 is at rest on the flange 21 the thrust of the back 50 will be transferred through the flange 17 to the flange 13 of the bar 11 so that the parallel levers 14 will be entirely relieved of all 55 strains placed upon the back when the seat is in use, the only strains brought on said levers being the strain of maintaining the back in its proper relation to the frame during its 60 swinging and reversing movement. The flanges 13 and 17 are terminated as described in order to permit the upper ends of the levers 14 to extend in between said flanges to the studs 15 and to properly operate between the enlargements 12 and 18 as the back is 65 swung from one position to another.

The flange 20 is perpendicular to the longitudinal center line of the back-standard 16 so that when said flange is at rest on the

flange 21 of the end frame the standard 16 inclines slightly rearwardly, as shown clearly in Fig. 1.

Rigidly mounted on the operating rod 9 near the ends of the back-supporting bars 11 are sleeves 22, each carrying at one end an upwardly extending crank arm 23 and at its other end radial wings 24 which fit slots in the inner end of the bar 11, shown clearly in Figs. 3 and 12. By reason of these wings 75 the sleeve 22 and rigidly connected rod 9 75 move with the connected bar 11. The outer end of the crank arm 23 is formed with a stud 25 which enters a vertical slot 26 in a cross link 27. The ends of this link are connected to the ends of depending crank arms 28 carried by sleeves 29 mounted to rotate on the connecting rails 2. Extending upwardly from these sleeves 29 are cushion-rocker arms 30. These arms are formed with 80 cylindrical heads 31 which carry upwardly 85 extending lugs 32. These lugs carry laterally extending fingers 33, shown clearly in Fig. 8.

On the bottom of the cushion 34 are secured metal strips 35 which are bent to form curved seats 36, said seats receiving the cylindrical heads 31 of the arms 30. The seats 36 are slotted at 37 to receive the lug 32; and at 38 to permit of the passage of the laterally extending finger 33. When the back standard 16 is in a vertical position midway between its forward and rearward positions the cushion-rocker arms extend inwardly and upwardly as shown in Fig. 2, and the 100 lateral fingers are in register with the slots 38 so that the cushion with the strips 35 may be disengaged from the cushion-rocker arms. When the back standard 16 is moved to one side or the other of its central position the 105 finger 33 is carried out of register with the slot 38 and the cushion is thereby locked to the rocker arms and cannot be detached therefrom until the back is again brought to its central position. This is of great advantage for the reason that it prevents the 110 accidental displacement of the cushion.

The crank arms 28 and the cushion-rocker arms 30 are so disposed that when the back standard is at rest on either flange 21 that 115 arm which is supporting the front portion of the cushion will be in a directly vertical position so that the strain of supporting the cushion will be delivered directly through said arm to the front connecting rail. The 120 rocker arm directly beneath the back will be thrown down to such a position as to permit the rear portion of the seat to come to rest on the rear connecting rail so that said 125 cushion-rocker arm will be relieved of the strain of supporting the cushion and the weight placed thereon. This is shown clearly in Fig. 1. It will, of course, be understood that when the back is swung to the left and the flange 20 is brought to rest on the 130

the flange 21 at the left-hand end of the end frame the positions of the cushion-rocker arms will be exactly the reverse of that shown in Fig. 1. This position of the cushion-rocker arms also gives the desired downward and rearward inclination of the cushion as indicated in dotted lines in Fig. 1; and, of course, this position of the cushion will be reversed with the reversal of the other parts when the back is moved from the right-hand end of the supporting frame to the left-hand end thereof, as viewed in Fig. 1 of the drawings.

The connecting rails 2 are connected together near each of their ends by a rigid bar 39. To this bar, directly over the operating rod 9, is pivoted a swinging support 40 for the foot rest 41. The foot rest bar 41 extends from one supporting bar 40 at one end of the seat support to the other bar 40 at the opposite end of the support. The foot rest bar 40 is slotted at 42 for the passage of the operating rod 9. Secured to the operating rod, adjacent each support 40 is a crank arm 43 formed with a stud 44 which enters and works in a longitudinally extending slot 45 which extends upwardly from the slot 42 at the center of the supporting bar. It is manifest that as the operating rod 9 is rotated by swinging the back from one side to the other of the seat the crank arm 43 will swing the foot rest supporting bars in the same direction as the movement of the back so that when the parts are at rest the foot rest is directly below the back, as shown in Fig. 1. The stud 44 of the crank arm 43 remains at all times in the slot 45 and acts as a lock to hold the foot rest arms in a fixed position when the back is at rest. This prevents any movement of the foot rest by any strains brought directly upon it. It is manifest that the foot rest will remain stationary and can only be moved through the movement of the back.

It will, of course, be understood that while the operating parts are shown for only one end of the seat the said parts may be duplicated at the opposite end or equivalent mechanism may be used. It is thought to be unnecessary to duplicate the illustrations by showing the operating parts at both ends of the seat.

It will also be understood that my invention is not limited to the exact details of construction described, but that it is as broad as is indicated by the following claims.

What I claim is:

1. A car seat comprising a support, a back-supporting bar pivoted at its lower end in said support, a back standard pivoted to the upper end of the back-supporting bar, a pair of levers pivoted at their lower ends to the support on opposite sides of and equal distances from the pivot of the back-sup-

porting bar, the upper ends of said levers being pivoted to the back standard on opposite sides of and equal distances from the center of the pivot of said standard, a stop carried by the support near each longitudinal edge of the seat, a stop carried by the back standard and adapted to rest against the stop on the support when the back is in either of its positions, a circular bearing flange at the upper end of the back-supporting bar, a circular bearing flange at the lower end of the back standard and fitting within and bearing against the circular flange of the back-supporting bar, said flanges being concentric with the pivot between the back supporting bar and the back standard and inclosing the upper pivots of the said pair of levers.

2. In a car-seat, the combination of a support, a back-supporting bar pivoted at its lower end thereto, and provided with a circular bearing flange at its upper end, a back standard having a circular bearing flange adjacent its lower end, one of said flanges fitting within the other, to form an interlocking pivotal bearing, a back carried by said standard, adapted to have seating positions at the forward and rear edges of the seat, in which it is inclined upwardly and rearwardly from the seat, said support having supporting surfaces thereon adjacent the forward and rear edges thereof, means on said standard affording a bearing surface, adapted to come into supporting contact with one or the other of said supporting surfaces when the back is moved into one or the other of its seating positions, and means for causing the back to assume the desired inclination as it approaches each of its seating positions on being reversed, and for controlling the inclination of the back during its movement of reversal; said circular bearing flanges being so arranged that pressure will be transmitted therethrough from the standard to said bar, when said back is in one of its seating positions, substantially as set forth.

3. In a car-seat, the combination of a support, a back-supporting bar pivoted at its lower end thereto, and provided with a circular bearing flange at its upper end, a back standard having a circular bearing flange adjacent its lower end, one of said flanges fitting within the other, to form an interlocking pivotal bearing, a back carried by said standard, adapted to have seating positions at the forward and rear edges of the seat, said support having stops thereon adjacent the forward and rear edges thereof, a stop on said standard, adapted to come into contact with one or the other of said support stops when the back is moved into one or the other of its seating positions, and means for causing the back to assume a desired angular position as it approaches

- each of its seating positions on being reversed, and for controlling its angular position during its movement of reversal; said circular bearing flanges being so arranged
- 5 as to transmit downward thrust of said back to said bar, and also to transmit to said bar stress caused by the reaction of either of said support stops against the stop on the standard, substantially as set forth.
- 10 4. A car seat comprising a support, an end plate carried thereby, a back-supporting bar pivoted at its lower end to said end plate and provided with a circular enlargement at its upper end, an outwardly extending bearing flange around said enlargement, a back standard formed with a circular enlargement at its lower end and pivoted to the center of the enlargement of the back-supporting bar, a circular bearing flange formed on the enlargement of the back standard and fitting within the flange of the back-supporting bar, said flanges being concentric with the pivot between the back supporting bar and the back standard,
- 15 20 a pair of levers pivoted at their lower ends on each side of and equal distances from the pivot of the back-supporting bar, the upper ends of said levers being pivoted to the back standard on each side of and equal distances from the center of the pivot of said standard, and within the circular bearing flanges downwardly and outwardly inclined flanges at each end of the end plate, a flange carried by the back standard and adapted to rest
- 25 30 35 on the inclined flange at the end of the end plate in either position of the back.
5. A car seat comprising supports, connecting rails mounted thereon and formed with cylindrical ends, end plates formed with sockets to receive the ends of the connecting rails and formed with bayonet slots, pins on the ends of the connecting rails adapted to enter said bayonet slots, means for locking the connecting rails against rotation, a cushion supported by the connecting rails and a back adapted to be supported by the end plates.
6. A car seat comprising a support, connecting rails mounted therein, cushion rocker arms rotatably mounted on said rails and formed with upwardly extending cushion supporting arms and downwardly extending crank arms, a cross link operatively connecting together the said crank arms, the cushion supporting arms being so mounted that one at the forward edge of the seat is vertically over the center of its connecting rail and the other at the rear is inclined to drop the rear of the seat on the rear connecting rail, a back, means for movably mounting said back to permit it to be swung from one longitudinal edge of the seat to the other, means operatively connecting said back supporting means to the cross link, whereby the cushion rocker arms will be re-

versed in position when the back is swung from one longitudinal edge of the seat to the other.

7. A car seat comprising a support, connecting rails mounted therein, cushion rocker arms rotatably mounted on said rails and formed with upwardly extending cushion supporting arms and downwardly extending crank arms, a cross link operatively connecting together the said crank arms, the cushion supporting arms being so mounted that one at the forward edge of the seat is vertically over the center of its connecting rail and the other at the rear is inclined to drop the rear of the seat on the rear connecting rail, a rotatable operating rod, back supporting bars connected to said operating rod and adapted to rotate it as said back supporting bars are swung from one edge of the seat to the other, a crank arm carried by said operating rod and adapted to engage the cross link, whereby as the back supporting bars are swung from one position to another the cross link will be moved by the crank arm and the positions of the cushion rocker arms will be reversed.

8. A car seat comprising connecting rails, rotatable cushion rocker arms mounted thereon, a cushion, sockets carried by said cushion, means carried by the cushion rocker arms to interlock with said sockets, said sockets being detachable from the arms only when the cushion is in a horizontal position, a back, a swinging support for said back, and means connecting said swinging support to the cushion rocker arms to reverse the position of said arms when the position of the back is reversed, said means moving the cushion into horizontal position when the back is vertical substantially midway between the longitudinal edges of the seat.

9. A car seat comprising connecting rails, rotatable cushion-rocker arms mounted thereon, a cushion, sockets carried by said cushion, means carried by the cushion-rocker arms to interlock with said sockets, said sockets being detachable from the arms only when the cushion is in a horizontal position, a back, a swinging support for said back, and means connecting said swinging support to the cushion-rocker arms to reverse the position of said arms when the position of the back is reversed.

10. A car seat comprising a support, connecting rails mounted therein, cushion rocker arms rotatably mounted on said rails and formed with upwardly extending cushion supporting arms and downwardly extending crank arms, a cross link operatively connecting together the said crank arms, the cushion supporting arms being so mounted that one at the forward edge of the seat is vertically over the center of its connecting rail and the other at the rear is inclined to drop the rear of the seat on the rear connecting rail, a back, means for movably mounting said back to permit it to be swung from one longitudinal edge of the seat to the other, means operatively connecting said back supporting means to the cross link, whereby the cushion rocker arms will be re-

- the rear connecting rail, a cushion, sockets carried by said cushion, means carried by the cushion supporting arms to interlock the said sockets, said sockets being detachable from the arms only when the cushion is in a horizontal position, a back, means for movably mounting said back to permit it to be swung from one longitudinal edge of the seat to the other, and means operatively connecting said back supporting means to the cross link, said means bringing the cushion to a horizontal position when the back is midway between the longitudinal edges of the seat.
11. A car seat comprising a support, an operating rod, a back supporting bar rigidly mounted on said operating rod, a back supported by said bar and adapted to be swung from one longitudinal edge of the seat to the other, a depending foot-rest-carrying bar pivoted in the support directly above the operating rod and extending below the said rod, said bar being formed with a segmental slot to receive the operating rod, an upwardly extending crank arm connected to the operating rod, and a pin on said crank engaging a vertical slot in the foot-rest-carrying bar and between the pivot of said bar and the operating rod, whereby the foot-rest-carrying bar will be swung together with the back supporting bar to maintain the foot-rest directly below the back.
12. A car seat comprising supports, connecting rails, end plates formed with sockets to receive the ends of the connecting rails and formed with bayonet slots, pins on the ends of the connecting rails adapted to enter said slots, means carried by the supports and engaging the connecting rails to lock said rails against rotation, an operating rod extending between the end plates, sockets on the end plates to receive the ends of said operating rod, back-supporting bars connected to the operating rod and adapted to rotate it, and a cushion supported by the connecting rails, whereby the bayonet-slot-and-pin connection between the end plates
- and the connecting rails serves as means for properly spacing the end plates to receive the operating rod.
13. A car seat comprising supports, connecting rails, end plates, means for securing said plates to the connecting rails, an operating rod, sockets on the end plates to receive the ends of said rod, a sleeve rigidly connected to the operating rod near one end thereof and formed with an upwardly extending crank arm at one end, and with radial locking wings at the other end thereof, cushion-supporting rocker arms mounted on the connecting rails, a cross link connecting said rocker arms together, means connecting said cross link to the end of the said crank arm, a cushion supported by the said rocker arms, a back-supporting bar mounted on the operating rod and formed with slots to receive the radial arms of the said sleeve to lock said back-supporting bar to the operating rod, and a back carried by said back-supporting bar.
14. In a car-seat, the combination of a support having longitudinally projecting portions, cushion rocker-arms rotatably mounted on said support, a cushion frame having means for a pivotal bearing connection with the upper ends of said arms, a back, supporting means therefor adapted to permit the back to be swung from one longitudinal edge of the seat to the other, means connecting said back-supporting means to said rocker-arms whereby the latter will be oscillated when the back is reversed, said rocker-arms being so mounted and connected to said back-supporting means that one at the forward edge of the seat stands vertically over its bearing on said support and the other at the rear extends at such an angle as to cause the rear of the cushion-frame to rest directly on one of said longitudinally projecting support portions, in each extreme position of the back, substantially as set forth.

In testimony whereof I hereunto affix my signature.

CLARENCE L. THOMPSON.
